UNITED STATES PATENT OFFICE.

EMIL GREINER, OF NEW YORK, N. Y.

DESIGN FOR A BOTTLE.

SPECIFICATION forming part of Design No. 34,474, dated May 7, 1901.

Application filed March 27, 1901. Serial No. 53,151. Term of patent 7 years.

To all whom it may concern:

Be it known that I, EMIL GREINER, a citizen of the United States of America, residing in the borough of Bronx, New York city, in 5 the county and State of New York, have invented and produced a new and original Design for a Bottle, of which the following is a specification, reference being had to the accompanying drawings, forming a part thereof.

10 The accompanying drawings represent the design which embodies my invention.

Figure 1 shows the design in side elevation, and Fig. 2 is a top view.

The leading feature of my invention consists in a bottle which comprises two separate tubes which end at the top in substantially the same plane. One of the tubes runs from the top down parallel to and alongside the other straight tube and is bent sidewise 20 near the end of the straight tube, forming a curve. Then it passes through the side wall of the top of the bottle and extends inside downward in an angular or inclined direction, so that its lower end is in the center of

the bottle. The straight tube has a capillary bore and is graduated. It rises from the center of the top of the bottle. The bent tube has a relatively large diameter.

The drawings illustrate a bottle, in which 1 represents the elongated bottle proper. 30

2 is the graduated capillary tube rising from the top of the bottle in the center and showing the graduations 3.

4 is the side or filling tube.

5 is the bent portion or curve, and 6 represents the inclined continuation of the tube 4 within the bottle. 35

Having thus described my invention, I claim—

The design for a bottle substantially as 40 shown and described.

In testimony whereof I affix my signature in the presence of two subscribing witnesses.

EMIL GREINER.
